Primary Examiner — L. A. Grabenstetter

Assistant Examiner — Bethany Louise Mallino

CLAIM

The ornamental design for a car seat protector as shown and described.

DESCRIPTION

FIG. 1 is a top plan view of a car seat protector, showing my design;

FIG. 2 is a bottom plan view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a bottom perspective view thereof; and,

FIG. 8 is a top perspective view thereof.

The broken lines in the drawings are for the purpose of illustrating environmental context of the article that form no part of the claimed design.

1 Claim, 7 Drawing Sheets
